UNITED STATES PATENT OFFICE

LEON W. STETSON, OF WEST NEWTON, MASSACHUSETTS

DESIGN FOR A SHOE

Application filed May 22, 1931. Serial No. 39,929. Term of patent 14 years.

To all whom it may concern:

Be it known that I, LEON W. STETSON, a citizen of the United States, residing at West Newton, county of Middlesex, Commonwealth of Massachusetts, have invented a new, original, and ornamental Design for a Shoe, of which the following is a specification, reference being had to the accompanying drawing, forming a part thereof.

The figure is a side elevation of a shoe showing my new design. The opposite or inside of the shoe is plain.

I claim:

The ornamental design for a shoe as shown and described.

LEON W. STETSON.
